UNITED STATES PATENT OFFICE.

THOMAS PATTERSON, OF BOSTON, MASSACHUSETTS.

FUSE-BLOCK.

SPECIFICATION forming part of Letters Patent No. 426,057, dated April 22, 1890.

Application filed December 30, 1889. Serial No. 335,365. (No model.)

To all whom it may concern:

Be it known that I, THOMAS PATTERSON, of Boston, county of Suffolk, State of Massachusetts, have invented an Improvement in 5 Safety Switch or Cut-Out for Electric Circuits, of which the following description, in connection with the accompanying drawings, is a specification, like letters and figures on the drawings representing like parts.

10 This invention has for its object to construct a safety switch or cut-out for electric circuits.

In accordance with this invention a block 15 of wood or equivalent material has formed in it a groove or passage, which is lined with asbestos paper or equivalent material. Two blocks are placed in the groove or passage—one at each end—and a fuse-wire of German silver or equivalent is held taut between the

20 two blocks by means of a spring. A suitable cover is provided for the groove or passage, which will be lined with asbestos paper or equivalent, to thereby totally conceal the fuse-wire and its tension-spring in an asbestos envelope contained in the blocks.

In carrying out my invention I may arrange as many fuse-wires in series as desired, and hence the block may be provided with several grooves or passages.

25 Figure 1 shows in plan view a safety switch or cut-out embodying this invention, the cover being removed, it showing two cut-outs arranged side by side; Fig. 2, a cross-sectional view of the switch or cut-out shown in Fig. 1, the cover being placed in position.

The block *a*, of wood or other suitable material, has formed in it one or more grooves or passages *a'*. Each groove or passage *a'* is lined with asbestos paper or equivalent ma-

terial *a*². Two metallic blocks *a*³ *a*⁴ are placed 40 in each groove *a'*—one at each end—and a fuse-wire *b*, of German silver or other suitable material, is fastened to one of the blocks, as *a*⁴, and is held taut by a spiral spring *b'*, attached to the other block *a*³. A cover *c* is 45 made for the block *a*, which has a lining *c'*, of asbestos paper or equivalent material, and the cover is held in place on the block *a* by screws 2 or equivalent fastenings. The terminals of the circuit are connected with the 50 blocks *a*³ *a*⁴, so that the current passes through the blocks and through the spiral spring and fuse-wire. Upon the presence of an abnormal current upon the line, the fuse-wire is instantly heated and, aided by the 55 spring *b'*, is ruptured, and the arc which may form soon burns out in the asbestos-lined box, so that no harm can be done.

When the switch or cut-out herein described is employed for outside work, it may 60 be placed in a water-proof and non-combustible box of insulating material.

I claim—

The block *a*, having one or more grooves or 65 passages lined with asbestos paper, combined with a fuse-wire placed in said groove or passage, and a spring for holding it taut, and a lined cover for the block, which conceals the fuse-wire and spring within the groove or passage *a'*, substantially as described. 70

In testimony whereof I have signed my name to this specification in the presence of two subscribing witnesses.

THOMAS PATTERSON.
